UNITED STATES PATENT OFFICE

2,511,040

DEVICE FOR SUPPORTING WALLPAPER
TO BE HUNG

Arthur M. Boone, Doucette, Tex.

Application August 20, 1946, Serial No. 691,806

2 Claims. (Cl. 216—4)

1

My invention relates to tools and more particularly to a device for supporting wall paper to be hung, it being understood that the device herein contemplated is to be used in combination with the regular, well-known tools of the wall papering trade.

The object of my invention is to provide a device for supporting wall paper to be hung adapted to support wall-paper of different widths in vertically hanging position.

Another object of my invention is to provide a device for supporting wall paper to be hung which is supported on rollers so that it can be moved across a floor into any desired position.

A further object of my invention is to provide a device for supporting wall paper to be hung having an extensible supporting column to raise the wall-paper which is supported in hanging position by the tool, to any desired height, within the adjustable limitations of the device, on the wall to which the paper is to be attached.

A still further object of my invention is to provide a device for supporting wall paper to be hung having an extensible supporting column and equipped with caster rollers, so that the device may be freely moved about into desired position.

Other objects of my invention may appear in the following specification describing my invention with reference to the accompanying drawing illustrating a preferred embodiment of my invention.

It is however to be understood that my invention is not to be limited or restricted to the exact construction and combination of parts shown in the drawing and described in the specification, but that such changes and modifications can be made which fall within the scope of the claims appended hereto.

In the drawing:

Figure 1 is an elevational front view of the paper supporting device according to my invention.

Figure 2 is an end view of Figure 1.

Figure 3 is an enlarged sectional view taken on line 3—3 in Figure 1.

Figure 4 is a detail view in an enlarged scale taken on line 4—4 in Figure 2 and,

Figure 5 is a sectional vertical view taken through one of the extensible joints of the supporting column.

Referring now in detail to the drawing, the device for supporting wall paper to be hung comprises a supporting column 10 embodying a plurality of tapered tubular sections 11 arranged

2

one within the other for extensible and collapsible movement relative to each other. The lowermost or outer of these sections 11 includes a base portion 12, secured thereto by any desired means and designed to carry a plurality of casters 13. The outer section 11 is provided adjacent the upper extremity thereof, with an annular ring 15 projecting beyond the outer surface of the section and so disposed as to form an annular groove on the inner surface of said section. The innermost section 11 is provided adjacent the lower extremity thereof with a similar annular ring 15 also forming a complementary groove 14 on the inner surface of said section. Each of the intermediate sections of the column is provided with an annular ring 15 adjacent both the upper and lower extremities thereof, each of such outwardly projecting rings being formed so as to provide a complementary groove 14 on the inner surface of the section. As will be readily apparent from an examination of Figure 5 of the drawings, when the column is extended the annular groove 14 of each section receives and retains therein the annular ring 15 of the adjacent section.

On the top of the uppermost column part 11 a sleeve 16 is rotatably mounted and from this sleeve 16 two bracket arms 17 extend laterally and upwardly. The ends 18 of the bracket arms 17 extend straight upwardly, as clearly shown in Figure 1.

A roller 19, preferably made from hard rubber or the like, has a metal rod 20 extending therethrough which is rotatably arranged in the upright extending ends 18 of the bracket arms 17 adjacent to the upper ends thereof.

A guide rod 21 extends between the bracket rod ends 18 underneath the roller 19 and two curved brackets 22 are slidably mounted on the guide rod 21. The upper ends of the brackets 22 are arranged above the roller 19 and on each of these upper ends a lever arm 23 is pivotally mounted. Each lever arm 23 extends inwardly and outwardly beyond the curved bracket 22, and on the inner end of each lever arm 23 a small wheel 24 is arranged, so that the weight of the wheel 24 plus the inner portion of the lever arm 23 urges the wheel into contact with the roller 19.

From the above description it is easy to understand that after the column 10, which is normally designed to remain in collapsed position, has been manually lifted to the desired height, within the structural adjustable limits of the device, a strip of wall-paper 25 can be arranged in hanging position over the roller 19 and will

be held in position by the wheels 24 pressing against the paper. The tool can then be rolled adjacent to the wall and the paper can be attached to the wall in the usual well known manner.

If it is desired to paper the ceiling of a room, the main supporting column 10 is extended upwardly as described hereabove and the paper applied to the ceiling in the usual well known manner.

In the same manner a border or the like can be applied to the ceiling or to the wall of a room.

To further detail the operation of the device, paste is applied to a strip of wall paper in the customary fashion. An extremity of the strip of paper is then placed upon the supporting roller 19 and the curved brackets 22 are adjusted in accordance with the width of this strip, with the rollers 24 in contacting engagement with the portion of the wall paper lying upon the supporting roller. The column 10 is then extended as many sections as the height of the room and the limitations of the device will permit, the strip of wall paper hanging vertically from the supporting roller. The device is then rolled to a desired position and the strip of paper is affixed to wall or ceiling in the usual manner.

Having described my invention I claim as new and desire to secure by Letters Patent:

1. In a supporting device for wall paper to be hung, a supporting column, a sleeve rotatably mounted on the top of said column, bracket arms extending laterally from said sleeve and carried by the latter, a rotatable roller extending between said arms and carried by the latter for supporting a strip of wall paper thereon, a guide rod arranged contiguous to said roller and supported in said arms, a pair of curved brackets arranged in facing relation with respect to said roller and slidably mounted on said guide rod, a clamping lever extending transversely of each of said brackets and pivotally secured to the latter, and a rotatable wheel on the inner end of each of said levers and positioned transversely of said roller for frictionally engaging the strip of wall paper when supported on said roller.

2. In a supporting device for wall paper to be hung, a supporting column, a sleeve rotatably mounted on the top of said column, bracket arms extending laterally from said sleeve and carried by the latter, a rotatable roller extending between said arms and carried by the latter for supporting a strip of wall paper thereon, a guide rod arranged contiguous to said roller and supported in said arms, a pair of curved brackets arranged in facing relation with respect to said roller and slidably mounted on said guide rod, a clamping lever extending transversely of each of said brackets and pivotally secured to the latter, and a rotatable wheel on the inner end of each of said levers and positioned transversely of said roller for frictionally engaging the strip of wall paper when supported on said roller, said column embodying a plurality of tapered tubular sections arranged one within the other and mounted for extensible and collapsible movement relative to each other, the outermost of said sections having an annular ring adjacent its upper end, the innermost of said sections having an annular ring adjacent its lower end, the intermediate sections being each provided with an annular ring adjacent the lower and upper ends thereof, each of said rings being arranged so as to project from the outer surface of the section and form an annular groove on the inner surface of the section complementary to said ring, the annular groove of each of said sections receiving the annular ring of the adjacent section upon extensible movement of the respective sections.

ARTHUR M. BOONE.
